SNOW AUGER

Robert A. Mittelstadt, Burnsville, and John M. Berner, Minneapolis, Minn., assignors to Toro Manufacturing Corporation, Minneapolis, Minn.

Filed Sept. 23, 1971, Ser. No. 183,302

Term of patent 14 years

Int. Cl. D15—03

U.S. Cl. D35—2 B

FIG. 2

FIG. 3

FIG. 1

FIG. 1 is a perspective view of a snow auger embodying our design;

FIG. 2 is a front view thereof; and

FIG. 3 is a side view thereof.

The broken line illustration of a snow thrower illustrates the environmental structure and intended use of the claimed design for a snow auger and is shown for illustrative purposes only.

We claim:

The ornamental design for a snow auger, as shown and described.
